UNITED STATES PATENT OFFICE.

MONROE ELLIOTT JOHNSON, OF PITTSBURG, KANSAS.

WEATHER-BOARDING GAGE.

SPECIFICATION forming part of Letters Patent No. 338,156, dated March 16, 1886.

Application filed January 28, 1886. Serial No. 190,138. (No model.)

To all whom it may concern:

Be it known that I, MONROE ELLIOTT JOHNSON, a citizen of the United States of America, residing at Pittsburg, in the county of Crawford and State of Kansas, have invented certain new and useful Improvements in Weather-Boarding Gages; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in weather-boarding gages, the object of the same being designed to provide a tool or implement which can be readily manipulated so as to serve as a guide and support for placing weather-boards in place.

20 In the accompanying drawings, which illustrate my invention, Figure 1 is a perspective view of a weather-boarding gage constructed in accordance with my improvement, and 25 Fig. 2 is a vertical longitudinal section showing my improvement applied.

A refers to the main frame or portion of the implement, said portion consisting of an upwardly-extending piece, B, which has formed 30 integrally therewith an outwardly-projecting screw-threaded portion, C, which is also provided at its lower end with a heel-piece, D, which projects substantially at right angles with the main body portion B. The heel portion D is recessed for the reception of a laterally-adjustable piece, D', which is provided 35 with an upwardly-projecting portion, d, which is adapted to be placed under one of the weather-boards which has been secured in position. The piece D' has formed integrally therewith a tongue, which enters the recess in the heel-piece D, and is secured thereon by a set-screw, this adjustable member adapting 40 the implement to be used with boards of different thicknesses. The body portion B tapers 45 from the outwardly-projecting screw-threaded portion upwardly, and it is provided centrally with a groove or dovetailed center portion, over which fits the rest or gage E, said 50 rest or gage being secured in place by a thumb-screw, e. The gage or rest consists, essen-

tially, of an angular block, which is provided with an upwardly-extending portion, f, and a dovetail recess which fits over the dovetail projecting portion B.

55 The screw-threaded portion C is adapted to receive the correspondingly-threaded handle C', which has rigidly secured thereto in any suitable manner a central bar, G, which passes through an opening in the screw-threaded portion, and at its opposite end is provided with a washer, g, which is secured thereto by a screw which enters the threaded recess in the end of the bar G. The washer g lies normally within a recess, g', in the body portion 60 B. Instead of employing the washer g, the end of the bar G may be pointed, so that the same can be passed beyond the inner edge of the body portion. One of the sides of the body portion B is provided with suitable gage- 70 marks, so that the lap of the boards over each other can be adjusted.

The operation of my invention is as follows: The implement after having the parts 75 D' and E adjusted, the lower one to correspond with the thickness of the weather-board, and the upper adjustable portion, E, for the lap of the boards over each other, is then ready for use. The projecting portion d is first placed over the last weather- 80 board, and the handle C' is then turned or rotated so as to force the washer g against the outer edge of the fixed weather-board, thus securing the implement in position. The weather-board to be nailed in position is then 85 placed upon the rest or gage E, which will support and hold the same in place while being nailed. After said board has been nailed in position, by turning the handle the washer g will be caused to enter its recess, and the 90 pressure being removed the implement can be released and is ready to be placed in position under the fixed board.

I claim—

1. In a weather-boarding gage, a body portion having an outwardly-projecting screw-threaded member, C, a handle internally screw-threaded and provided with a follower, substantially as shown, and for the purpose set forth.

2. In a weather-boarding gage, a body portion having an outwardly-extending screw-thread-

4. In a weather - boarding gage, the body portion B, provided on its inner side with a recess and on its opposite side with an outwardly-extending screw-threaded portion, in combination with a handle located on said screw-threaded portion and carrying a bar, G, having a washer, g , secured thereto, and a foot with an upwardly-extending portion, substantially as and for the purpose set forth.

5. In a weather - boarding gage, a tapered body portion, B, having a dovetailed projection formed thereon, a gage or rest movably secured to said dovetailed projecting portion, b , to a rotary internally-screw-threaded handle b , which is adapted to engage with the outwardly-extending screw-threaded portion C, and provided with a follower which can be projected beyond the inner side of the body portion, and an adjustable foot, D', with an upwardly-projecting portion, d , the parts being organized substantially as shown, and for the purpose set forth.

4. In a weather - boarding gage, the body portion B, provided on its inner side with a recess and on its opposite side with an outwardly-extending screw-threaded portion, in combination with a handle located on said screw-threaded portion and carrying a bar, G, having a washer, g , secured thereto, and a foot with an upwardly-extending portion, substantially as and for the purpose set forth.

5. In testimony whereof I affix my signature in the presence of two witnesses.

MONROE ELLIOTT JOHNSON.

Witnesses:

WM. A. GANUTT,

RANDALL DRYDEN.
